UNITED STATES PATENT OFFICE.

WILLIAM McCALLUM, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 14,395, dated November 6, 1883.

Application filed August 23, 1883. Term of patent 3½ years.

To all whom it may concern:

Be it known that I, WILLIAM McCALLUM, of Yonkers, in the county of Westchester and State of New York, have invented and produced a new and original Design for a Carpet, of which the following is a full description, in connection with the accompanying photograph, which represents a face view of my new design for a carpet.

10 This invention relates to a new ornamentation for the border of a carpet or analogous fabric.

In the accompanying photograph are shown five parallel bars or stripes, *a b d e f*, which divide the carpet into four bands, *A, B, C*, and *D*, the band *C* being the broadest. In this band *C* are contained the representations of three flowering plants, *E, F*, and *G*. The plant *E* appears to grow from the band *D* over 15 the stripe *e*, and to connect its upper part with leaves *g* and *h* in the bands *B* and *A*, respectively. The plant *F* appears also to grow out of the band *D* and to extend into the bands *B*

and *A*, as shown. The plant *G* also appears to grow out of the band *D* and partly overlaps the stripe *d*. The stripe *a* is composed of dotted figures, the stripe *b* of octagonal figures and dots, the stripe *d* of parallel bars, the stripe *e* of parallel bars containing between them uprights or cross-bars, while the stripe *f* contains a zigzag line between parallel bars, all as shown. In the band *B*, beside the portions of the plants *E* and *F*, are also contained circular figures *i* and obliquely-placed bars *j*. The band *C* contains a checkered background, 20 on which the upper parts of the floral groups appear to be placed.

I claim—

The design for a carpet, the same consisting of the figures *A B C D E F G a b d e f g h i j*, 25 substantially as shown.

WILLIAM McCALLUM.
